UNITED STATES PATENT OFFICE.

ARTHUR R. SMITH, OF SCHENECTADY, NEW YORK, ASSIGNOR TO GENERAL ELECTRIC COMPANY, A CORPORATION OF NEW YORK.

ELECTRICAL APPARATUS.

1,426,921.

Specification of Letters Patent. Patented Aug. 22, 1922.

Application filed May 6, 1919. Serial No. 295,247.

To all whom it may concern:

Be it known that I, ARTHUR R. SMITH, a citizen of the United States, residing at Schenectady, in the county of Schenectady, 5 State of New York, have invented certain new and useful Improvements in Electrical Apparatus, of which the following is a specification.

My invention relates to electrical apparatus, particularly to switchboard structures, 10 using that term in its broadest meaning, and has for its object to provide a switchboard unit or supporting structure for electrical or other apparatus which is very 15 flexible in construction, may be more readily standardized than switch-board structures now in use, which requires less labor in its construction, which overcomes many undesirable features of present switchboard 20 structures, and which in other particulars, to be hereinafter described more in detail, is an improvement over switchboard structures heretofore known.

The term "switchboard" has come to have 25 a meaning in the art broader than is indicated by the term itself, for such a structure may or may not carry switches or switch controlling devices but may merely serve as a support for indicating or recording instruments and like apparatus or may carry control 30 and regulating apparatus for steam and other equipments. Switchboard structures now in use comprise one or more panels of slate, marble or similar insulating material, upon 35 which is mounted all the devices used to operate and control electrical or other equipment, the particular assortment and arrangement of such devices being determined by the specific equipment to be controlled. These devices include indicating 40 and recording meters and instruments, relays, regulating and other control instruments of all kinds, switches for electrically controlling larger switches and other apparatus 45 and devices too numerous to mention, but in general all devices which it is possible and desirable to bring under the immediate observation or manipulation of the station operator. All these devices, and 50 any combination of them, I hereinafter include in the term "switchboard devices." As before stated, however, a "switchboard," as that term is now understood, may or may not carry switches, but the term now means 55 the assembly of any combination of switch-

board devices on a suitable support or supporting structure, and it is with such broad meaning that the term is used in this specification and claims.

My invention will perhaps be better understood after a brief consideration of present switchboard practice and certain disadvantages of undesirable features of present switchboard structures. The present switchboard comprises panels of slate, marble or 60 like material supported by a suitable framework. The location of such a switchboard in a station is often difficult, as to support the board and hide and protect the back, due to exposed live parts, it is necessary to install the same with its back to a wall, while at the same time, due consideration must be made for windows in order to provide satisfactory lighting conditions. In the installation, consideration must be given to 65 future expansion, which necessitates leaving open spaces for panels to be filled in at some later date or by providing blank panels, both arrangements being unsatisfactory. 70 Furthermore, for present switchboards, it is necessary to carry a large stock of slate or 75 marble in various sizes which is heavy material, difficult to handle, easily breakable, expensive to ship and requires care to prepare the same for shipment. Furthermore, 80 little dependence is made in present practice upon the insulating qualities of the slate or marble so that many of the devices mounted thereon are separately insulated 85 from the panel. 90

The conductors connected to the devices are held in place on the back of the switchboard by cleats and other accessories, requiring drilling of the panel and these connections together with exposed live parts 95 produce a certain risk as regards possible short circuits, collect dust and, due to changes of wiring connections, present an unsightly appearance.

It is common practice, at present, due to 100 difficulty of standardization, to make separate drawings and diagrams of the front and rear of each switchboard panel, to provide full sized paper templets serving as a pattern for drilling the holes for mounting 105 the devices. The devices are then suitably mounted, all necessary wiring done and the installation set up and inspected before the switchboard is shipped. Then for shipment, the switchboard is dismantled and 110

the devices shipped separately, all this work requiring considerable time and labor.

According to my invention, I substantially overcome the undesirable features of present switchboard structures, as outlined, by providing a novel and improved supporting structure which is unitary in construction and in its simplest form comprises a hollow pedestal member into which the conduits lead, and a hollow pipe or tubular member mounted thereon provided with means whereby the various switchboard devices may be secured thereto. This tubular member is an upright portion carried by the pedestal through which all conductors pass to the devices carried thereon. It is also possible, under some circumstances, to have horizontally extending tubular portions if occasion desired. The pedestal member is provided with a terminal board within its inclosure to which the various conductors, extending through the pipe member, are connected through fuses and the like, to the conduit conductors.

The novel features which I believe to be characteristic of my invention will be definitely indicated in the claims appended hereto while the features of construction and mode of operation will be understood by reference to the following description taken in connection with the accompanying drawings in which:

Fig. 1 shows in front elevation a switchboard structure embodying my invention in which various combinations of switchboard devices are used for each unit; Fig. 2 is a side elevation, partly in section, of a switchboard unit embodying my invention adapted for the control of a large switch; Fig. 3 is a front elevation of a portion of the device shown in Fig. 2; Figs. 4 and 5 are front and side elevations respectively of the pedestal portion of my switchboard structure. Figs. 6, 7, 8 and 9 are detail views of a portion of my switchboard; Fig. 10 is a sectional view of the pipe member of my structure showing various means whereby the switchboard devices may be secured thereto; Figs. 11 and 12 illustrate different methods of mounting switchboard devices on the hollow member and Fig. 13 is a plan view of separate instrument and control equipments for a large plant, showing one arrangement of the switchboard units.

As shown in Fig. 1, each switchboard unit 10, 11, 12 and 13 comprises a hollow and preferably vertical pipe or supporting member 15, which may be round or plural sided but preferably square, as shown in Fig. 10, and closed at its upper end by a suitable cap 16. At its base, the pipe or tubular member 15 is carried in and supported upon a pedestal or base member 17, preferably substantially conical or pyramidal in configuration. Distributed along its length, the pipe 15 is

provided with a plurality of openings or outlets, which may be provided with bushings, through which conductors may pass, caps or plugs 18 being provided for such openings when not in use. The various switchboard devices may be mounted upon or supported by the pipe 15 in various ways, one means of support being indicated in Figs. 11 and 12 wherein bracket arms or housings 20 are fastened in various ways to the pipe 15 and at their outer ends are attached to the devices or the device casings 21. From the back of each device, its conductors 22 pass to the interior of the pipe 15 through the suitable opening 23. As shown in Fig. 10, the switchboard devices may also be secured directly to the pipe member 15 through suitable attaching means or members 24, 25, 26, 27 mounted in openings provided in the pipe through which the conductors for the devices are adapted to pass. Members 24, 25 and 26 are provided with threaded portions to which the devices, having corresponding parts, are adapted to be secured, the conductors for such devices passing through the openings into the interior of the member 15 thereby concealing the same. These members 24, 25 and 26 are merely illustrative of various mechanical ways by which the devices may be secured to the pipe member either by bending over extension strips into the dotted line position, as shown by member 24, crimping or expanding in place, as shown by member 25 or by a flange portion, as shown by member 26. Member 27, on the other hand, shows a fourth method of attaching devices being threaded to the pipe member 15 and having an outer flange between which and the pipe, the device can be clamped or otherwise secured.

From the various devices, conductors 22 then pass through their respective openings in the pipe support 15, down through the hollow interior thereof to a terminal or distributing board 28 suitably supported within the pedestal 17, as best shown in Figs. 4 and 5. In this manner all the conductors 22 are protected by the casing of the pipe support and no wiring is exposed. The diameter of the pipe support 15 will be commensurate with the number of devices it can support and hence ample to take care of the conductors therefor.

These terminal boards 28 may be made in various forms but, in general, comprise, as shown in Fig. 4, a plate of insulating material upon which is mounted one set of terminal studs 29 to which is secured or anchored the ends of conductors 22 connected to the various switchboard devices and a second set of terminal studs 30 to which is secured the outgoing or conduit conductors 31 connected to the apparatus or equipment to be controlled. Between the terminal studs 29 and 30 for completion of their electrical circuit.

cuits, are mounted various devices such as fuses, testing jacks, etc. In the form of terminal board shown in Fig. 4, various recessed portions 32 are provided for the insertion of fuses 33 whereas in Figs. 8 and 9 recessed portions 32 are provided for ammeter, voltmeter or testing jacks 34 or other electrical instrumentalities. In Figs. 6 and 7, a modified construction of terminal board 10 is shown provided with insulating barriers 35 between which various connecting devices may be located. As an example of one such device, three conductors 22 are connected to one outgoing conductor 31 through a fuse 15 and common terminal plate 36. It will thus be apparent that any number of variations of connections may be utilized upon this terminal board structure whereby numerous functions may be performed. The separate 20 sets of terminal studs 29 and 30 provide a convenient and easy method of changing connections as desired without disturbing the other conductors and should it be desired to change the switchboard devices all 25 that is required is to disconnect its conductor or conductors 22 from its studs 29 and remove the device with its connection attached. Furthermore should devices be added in the future, a device is attached and its connection 30 22 dropped through the interior of the pipe support 15 and connected to the proper terminal 29, enough terminals being provided on the terminal board for the maximum number of devices which each pipe 35 support can carry. The terminal board is carried within the inclosure of the pedestal 17 which is provided with an opening and cover for the same, thus affording a very accessible and convenient location, at the same 40 time preventing the accumulation of dust and presenting always a very neat appearance. Fig. 5 indicates in dotted lines, how two such terminal or anchor boards may be disposed within each pedestal, if required. 45 The pedestal member 17 is preferably made with a flange portion 37 and a conduit box 38 depending therefrom, the flange portion 37 serving as a supporting means for the pedestal upon the floor or cement base 50 of the station, as shown in Fig. 4, while the conduit box portion 38 extends below the floor level and is provided with a plurality of openings 39 through which the various conduits 39^a pass, carrying the conductors 55 31 from the terminal board 28.

In Fig. 1, I have shown my novel form of switchboard unit with various combinations of switchboard devices carried thereby. Each unit may be a complete switchboard 60 in itself or the four units 10, 11, 12 and 13 taken together may form units of a switchboard. Unit 10 shows a switchboard panel or unit controlling a generator, upon member 15 of which is mounted, in vertical alignment, six switchboard devices 40 which may

be a voltmeter, ammeter, wattmeter, power factor meter, steam meter and temperature indicator or any combination of devices desired. Upon this unit is shown other devices upon the opposite side of the pipe 70 member 15, such devices being those which are not necessary for the operator to constantly observe, such as relays 41 and recording instruments 42, the back view of this unit being shown by unit 13. Immediately below these devices, is shown a group of control switches 43 for synchronizing for connecting various machines or lines to the meters individually, for controlling an oil switch, a turbine governor, a field rheostat 80 and field switch, or for any other purposes. The unit 11 shows a switchboard structure embodying my invention as an exciter panel having two indicating meters 44 and a voltage regulator 45. If it is desired to operate 85 oil switches, or rheostats or other heavy apparatus, separate pedestal supports may be provided conforming in design with the pedestals 17, upon which the operating handle and mechanism is mounted with any necessary automatic tripping devices. In unit 11 90 I have shown such a pedestal 46 mounted in front of pedestal 17 for the unit, which carries the operating lever 47 for operating a switch and automatic tripping devices 48 95 therefor.

In Fig. 2 I have shown in side elevation, a modified form of unit in which a different pedestal 49 is provided for the pipe member 15 carrying the switch operating lever 47 100 and automatic devices 48. In this figure the oil switch 50 to be controlled, is mounted in a chamber or compartment 51 and operated through a suitable connecting mechanism 52 extending through an opening in the wall of 105 the chamber. Upon the top of chamber 51, the switch leads are connected to the bus bars 53 through a suitable disconnecting switch 54, the top portion carrying live parts being protected by a suitable screen 55. In 110 Fig. 3, a front elevation of a portion of this structure is shown, giving an idea of the inconspicuous appearance of the switchboard unit. Mounted upon the pipe support 15 of this switch controlling unit are various 115 switchboard devices 56 as desired.

Referring again to Fig. 1, unit 12 is shown as a two circuit feeder panel carrying six instruments or meters 57 arranged in horizontal pairs near the top of the pipe 15. 120 Below these devices are shown four relays 58 also arranged in horizontal pairs. Upon separate pedestals 46 in front of unit 12 are carried operating levers 47 controlling, as already described, any heavy apparatus 125 which may be located in the rear of the unit or below the floor. A comparison of units 10, 11 and 12 indicates, by way of example, the variety of switchboard devices and the various combinations of the same which, ac- 130

cording to my invention, is possible to mount upon the pipe supporting member 15 to meet not only all present requirements but also any future extensions, for with used outlets covered by plugs 18 other devices may be added without difficulty. Unit 13 compared with any one of the others shows how completely the supporting member 15 may be utilized in carrying the switchboard devices.

In assembling the switchboard devices upon the pipe member 15, as before pointed out, the devices may be provided with a special casing adapted to be secured to the bushings 24, 25, 26 or 27 as shown in Fig. 10, this figure showing four different types of bushings by which the devices may be mounted with concealed connections. For mounting a single series of devices in alignment, a bracket construction similar to that shown in Fig. 11 may be used and for a double series of devices, similar to that shown upon unit 12 of Fig. 1 a bracket mounting to the side or offset from the pipe member may be used as shown in Fig. 12.

In Fig. 13 is shown a plan or layout of a station equipped with my improved switchboard construction comprising a group of switchboard units. Each of the units 59 are mounted with their pedestals 17 in alignment but in order that the various devices carried by these units may be observed from a central point, the pipe support members 15 are angularly disposed in the manner shown to enable the faces of the devices mounted thereon to all face toward a common point. This flexible arrangement is of particular advantage when bench boards of control switches 60 are used.

The advantages of the form of switchboard structure described will be apparent so that only a brief outline of the same will be given. This form of structure is very flexible as any number of devices and combinations of the same can be used, the devices can be readily standardized for various purposes, requiring only a few number of parts to be carried in stock. The parts are light, cheap to ship and non-breakable. No drawings, wiring connections, or templets are necessary nor is it necessary to assemble the unit and test the same before shipment. The pedestals, pipe members with caps and plugs 18 in the outlets can be shipped disassembled in a compact manner requiring little space and the various devices can be shipped direct from stock without installing the same. The switchboard units can be mounted in front of windows and in any desirable location without unduly impairing the lighting conditions. Other units may easily be added from time to time as needed and the unit itself adapted for the installation of other devices as

required for future needs. Each pipe member 15 is provided with a maximum number of outlets and all that is necessary to add a device, is to remove a plug 18 and attach the device with its connection to the terminal board 28. Likewise this flexibility enables an operator to change his devices upon the same unit or from one unit to another with ease and facility.

Furthermore, all wiring connections are protected and are free from dust while at the same time ready means is provided for all connections, within the pedestal 17 on the terminal board. This board again by its structural features provides a means whereby any change or arrangement of connections can be made as desired. Finally a large equipment of devices can be installed in a relatively small space without impairing the appearance of a station and the units themselves never appear unsightly.

What I claim as new and desire to secure by Letters Patent of the United States, is:—

1. A switchboard structure comprising a tubular member, a hollow pedestal supporting said member, a terminal board within said pedestal, switchboard devices carried by said member, and conductors for said devices passing from said devices along the interior of said member to said terminal board.

2. A switchboard structure comprising a hollow member provided with openings through the wall thereof, a hollow pedestal supporting member terminals within said pedestal for said hollow member, switchboard devices carried by said member, and conductors for said devices passing through said openings to the interior of said hollow member and along the interior thereof to said terminals.

3. A switchboard structure comprising a vertical tubular member provided with openings through the wall thereof, a supporting base for said member, a terminal board carried by said base, switchboard devices carried by said member, conductors passing from said devices through said openings to the interior of said member and through the same to said terminal board, and other conductors connected to said first mentioned conductors through said terminal board.

4. A switchboard structure comprising a tubular member provided with openings through the wall thereof, a hollow pedestal for said member, a terminal board within said pedestal, switchboard devices carried by said member, conductors passing from said devices through said openings to the interior of said member and through the same to said terminal board, a conduit box carried by said pedestal and extending be-

low the same, and other conductors extending into said conduit box and connected to said terminal board.

5. A switchboard structure comprising a substantially hollow base member, a tubular upright member carried by said base member and provided with a plurality of openings therein, switchboard devices, means whereby said devices may be detachably secured to said tubular member and conductors extending from said devices through said openings into said tubular member and concealed thereby.

6. In a supporting structure for switchboard devices, the combination with a hollow upright member provided with a predetermined number of openings therein, switchboard devices adapted to be detachably secured to said hollow member, conductors for said devices extending through said openings and carried within said hollow member, and means for closing said openings not in use.

7. A supporting structure for switchboard devices comprising a tubular supporting member provided with a plurality of openings therein, switchboard devices adapted to be detachably secured to said member, a hollow base member, a terminal board within said base member, conductors for said devices extending through said op-

enings into said tubular member and within said member to said terminal board, other conductors connected to said terminal board, and electrical instrumentalities carried by said terminal board adapted to be connected between said first and second mentioned conductors.

8. A switchboard comprising an elongated hollow member provided with openings through the wall thereof, an enclosed terminal board secured thereto at one end thereof, switchboard devices, means for supporting said devices upon said member, and conductors passing from said devices through said openings to the interior of said member and along the length of the interior thereof to said terminal board.

9. A supporting structure for switchboard devices comprising a hollow pedestal member, a vertical tubular member mounted on said pedestal and provided with a plurality of openings therein, means whereby switchboard devices may be mounted in said openings, a terminal board within said pedestal member, and conductors between said devices and said terminal board carried within said hollow vertical member.

In witness whereof, I have hereto set my hand this 5th day of May 1919.

ARTHUR R. SMITH.
